Attorney—Imirie, Smiley, Snyder and Butrum

ABSTRACT: A coin has three positions in the lock. In the first position, the coin will cause a detent member to be pivoted away from rotary passage of a stopper member provided on the locking bolt when a key is turned. In the second position, the coin will continuously retain the detent member in thus pivoted position. In the third position, the coin is held at the entrance to coinbox. Since the detent member is retained in the retreated position when the coin is in the second position, the locking bolt can be brought back to unlocking position as desired without affecting the indication of counter means.

COIN CONTROLLED LOCK

The present invention relates to a coin controlled lock, more particularly to a coin controlled lock having a key operated rotary locking bolt and employed in checking cabinets.

In the prior art lock of this kind, since a coin deposited in the lock will drop into the coinbox and a counter is operated each time the locking bolt is brought into locking position, the locking bolt can not be brought back into unlocking position once it is put into the locking position. It is very inconvenient for the user when he desires to open the cabinet again before removing a key.

The present invention is devised to overcome such difficulties of the prior art lock.

It is primary object of the present invention to provide a coin controlled lock which is brought into locked position by depositing a coin and then turning a key, and which is capable of being brought back into unlocking position as desired without causing the counter means to be operated even after it is once brought into locked position.

Another object of the present invention is to provide a coin controlled lock in which the deposited coin is caused to drop into the coinbox only after the removed key is inserted again into the lock and turned to open the same.

Still another object of the present invention is to provide a coin controlled lock which is inexpensive to manufacture, reliable in operation and convenient to use.

According to the present invention, there is provided a coin controlled lock comprising a frame member having a coin passage therethrough, a rotary locking bolt having a stopper means thereon and fixedly mounted on a shaft which is in turn rotatably mounted on said frame member and provided with a keyhole, a detent member pivotally mounted on said frame member and adapted to limit a rotation of said locking bolt when no coin is deposited, a retainer member pivotally mounted on said frame and adapted to retain said detent member in a position retreated from passage of said stopper means when the coin is deposited, and a means for retaining said coin in a position to cause said retainer member to be maintained in a position to hold said detent member in said retreated position.

Now, one preferable embodiment of the coin controlled lock according to the present invention will be described in detail by way of example hereinafter with reference to accompanying drawings, in which;

FIG. 1 is a front view showing the coin controlled lock according to the present invention.

FIG. 2 is a rear view showing the coin controlled lock in unlocked position.

FIG. 3 is a rear view showing the coin controlled lock in locked position.

FIG. 4 is a vertical section view taken along a line IV-IV in FIG. 2.

FIG. 5 is a vertical section view taken along a line V-V in FIG. 4.

FIG. 6 is a vertical section view taken along a line VI-VI in FIG. 4.

FIG. 7 is a view showing the relative position of essential members of the lock in unlocked position with the frame and guide plates removed.

FIG. 8 is a view similar to FIG. 7 in locked position, and

FIG. 9 is a view showing the relative position of the locking bolt according to this invention with reference to the locking member of the door intended to be locked by the lock of this invention.

Now, referring to drawings, particularly FIG. 1, a frame 1 of the coin controlled lock has a lock barrel 2 mounted thereon. The frame 1 is normally mounted on a checking cabinet (not shown) adjacent to the door thereof. A keyhole for receiving a key 3 is provided on a rotatable shaft 2a of the lock barrel. An axially slidable small pin 4 is located adjacent to innermost end of the rotatable shaft 2a (See FIG. 4). The pin 4 is mounted in such a manner as to be projected outwardly when

the key 3 is inserted into the keyhole and retracted when the key 3 is removed out of the keyhole. The key 3 is made removable only when the lock is in locked condition. A coin depositing opening 5 is provided in front of the frame 1 so as to have a coin deposited in parallel to front surface of the frame 1.

Referring to FIGS. 2-8, a face plate 6 is secured to front portion 1a of the frame 1. Also, a rear plate 7 is secured to the front portion 1a of the frame 1 in a side opposite to that of the face plate 6, with a spacer plate 8 inserted therebetween. The face plate 6, the front portion 1a of the frame 1, the spacer plate 8 and the rear plate 7 are secured together by suitable means such as machine screws. The front portion 1a of the frame 1 and the spacer plate 8 are cut out so as to form a coin passage R which is communicated to the coin depositing opening 5, see FIG. 4. As shown in FIGS. 4 and 6, the coin passage R is connected to a coin passage R' which is formed in the lower part of the lock by guide plates 9 and 11. The coin passage R' includes a rearwardly sloped portion R₁' as shown in FIG. 4 and an arcuate portion R₂' as shown in FIG. 6.

A L-shaped guide plate 10 is located in left side bottom corner in FIG. 2. An arcuate portion 11a of the guide plate 11 is located oppositely to the corner guide plate 10. As shown in FIGS. 2, 5, 6, the guide plate 11 is provided with an arcuate guide opening 11b, which will be described hereinafter, and also with a channel-shaped notch portion 11c in the upper edge thereof adjacent to the arcuate portion 11a.

As shown in FIGS. 2, 3, 7, 8, an actuating lever 12 is fixedly mounted on the rotatable shaft 2a, and provided with an arm having a bent end 12a adapted to be engaged with the arcuate guide opening 11b of the guide plate 11 so as to slide therewith. The bent end 12a engaged with the guide opening 11b is placed at top end of the guide opening 11b when the lock is in unlocked position. A counter operating lug 12b and a stopper member 12c are also provided on the actuating lever 12 at the end opposite to the bent end 12a.

A locking bolt 13 is fixedly mounted on the rotatable shaft 2a and rigidly connected to the actuating lever 12. A spring receiver pin 14 is provided on the locking bolt 13 in the intermediate portion thereof. Another stopper member 13a is formed on the locking bolt 13 at upper corner thereof so as to abut with a receiver lug 1a provided in the side of the frame 1 when the lock is in locked position. A leaf spring 15, which is bent as shown in FIG. 2, has one end secured to the frame 1 and the other end maintained in contact with the spring receiver pin 14. The locking bolt 13 is rotated counterclockwise in FIG. 2 when unlocked by action of this spring 15, thereby causing the bent end 12a of the actuating lever 12 rigidly connected to the locking bolt 13 to be engaged with the upper end of the arcuate guide opening 11b as described hereinabove.

An elongated opening (not shown) is provided in the side of the frame 1 so as to have the tip end of the locking bolt 13 exposed to the outside. As shown in FIG. 9, the locking bolt 13 in locked position will withhold a locking member 100, which is rotatably mounted on the door and connected to a suitable latch member (not shown) of the latter, also in a locked position through intervention of a pivot member 101 which is pivotally mounted on the door. Unlocked positions of the locking member 100 of the door, the pivot member 101 and the locking bolt 13 are shown in dotted lines. In this manner, the locking bolt 13 can lock the door without having the tip end projected out of the side surface of the frame 1.

A L-shaped kicker lever or retainer member 16 is pivotally mounted on the guide plate 11 by means of a pin 17. The kicker lever 16 is provided with a cam means 16a formed adjacent to the corner of L. One leg 16b of the kicker lever 16 is formed into arcuate configuration and laid over the guide opening 11b. The other leg of the kicker lever 16 has a bent tip end 16c, which is located in the coin passage R₂'. A spring 18 has one end secured to the guide plate 11 and the other end anchored on the lever 16 adjacent to the bent end 16c so as to urge the lever 16 counterclockwise as viewed in FIG. 2. A

stopper pin 19 is fixedly mounted on the guide plate 11 so as to receive the arcuate portion 16b of the kicker lever 16.

As shown in FIGS. 2 and 3, a first coin retainer lever 20 is pivotably mounted on the guide plate 9 by means of a pin 21 and biased clockwise as viewed in FIG. 2 by a spring 22. The first coin retainer lever 20 is provided with an extended arm 20a which is engaged with end of lower arm 23a of an intermediary lever 23. The intermediary lever 23 is pivotally mounted on the guide plate 11 by means of a pin 24. Tip end of the upper arm is maintained in contact with a bent end 12a of the actuating lever 12 when the lock is in unlocked position. In this condition, the coin retainer lever 20 is pivoted counterclockwise as viewed in FIG. 2 by action of the intermediary lever 23. Accordingly, an opening to coinbox will be opened.

As shown in FIG. 5, a detent lever 25 of L-shaped configuration is pivotally mounted on the guide plate 9 adjacent to upper edge thereof by means of a pin 26'. A lower leg of the detent lever 25 has a bent tip end 25a which is fitted into the notch portion 11c of the guide plate 11. A bent end 25b of upper leg of the detent lever 25 is located in an arcuate track or path of the stopper portion 12c of the actuator lever 12 when the lock is in unlocked position. A leaf spring 26 is mounted on the detent lever 25 so as to urge a retainer lever 28 which is to be described hereinafter. A spring 27 is provided on the detent lever 25 so as to urge the latter clockwise as viewed in FIG. 2. As shown in FIG. 3, a retainer lever 28 is pivotally mounted on the front portion 1a of the frame 1 by means of a pin 30 so as to retain an operating lever 31 of counter means 33 which will be described hereinafter. A spring 29 is mounted on the retainer lever 28 so as to bias the latter counterclockwise as viewed in FIG. 3. A projecting lower end of the retainer lever 28 is maintained in contact with upper end of the leaf spring 26.

The L-shaped operating lever 31 is pivotally mounted on the front portion of the frame 1 by a pin 32, see FIG. 2. A bent end 31a of the operating lever 31 is connected to a tension spring 34 of the counter means 33, and maintained in contact with a stopper means 33a provided on the counter means 33 when the lock is in unlocked condition as shown in FIG. 2.

A second coin retainer lever 36 is pivotably mounted on a support piece 35, which is fixedly mounted on the frame 1 in one side thereof, see FIG. 2. The second coin retainer lever 36 will pivot about a pin 38, and has a bent end 36a extended into the coin passage R₂' as shown in FIG. 4. A flat end portion 36b of the second coin retainer lever 36 is maintained at all times in contact with the slidable small pin 4 provided adjacent to the rear end of the rotatable shaft 2a, by action of a spring 37, which is mounted on the retainer lever 36 so as to bias the same counterclockwise as viewed in FIG. 4. As shown in FIGS. 3, 8, the second coin retainer lever 36 will act to retain the coin in a position C2 (FIG. 8) within the coin passage. The coin in this position will hold the bent end 16c of the kicker lever 16 in a raised position, thereby bringing the cam means 16a of the kicker lever 16 into a position to raise the bent end 25a of the detent lever 25 so as to cause the detent lever 25 to be pivoted counterclockwise as viewed in FIG. 8.

Accordingly, as long as the coin is retained in position C2 (FIG. 8) by action of the bent end 36a of the coin retainer lever 36, the detent lever 25 is in the position retreated from the rotary track or passage of the stopper member 12c of the actuating lever 12, which position will permit the locking block 13 to be swung into the locking position. This second coin retainer lever 36 will constitute one important feature inherent to the present invention.

In operation, when the key 3 is turned in a direction of locking, that is, clockwise as viewed in FIG. 2 from the unlocked position without any coin deposited, the locking bolt 13 and the actuating lever 12 will be rotated together until the pin 14 passes over a bent portion of the spring 15, but the stopper member 12c of the actuating lever 12 will abut with the bent end 25b of the detent lever 25 thereby preventing the locking bolt 13 from being rotated further. Therefore, the lock is not brought into locked position.

If the coin is deposited through the opening 5, it will fall down the coin passage R and come to position C1 in FIG. 7 wherein the coin is held at one point in the periphery by the bent end 25a of the detent lever 25. In this condition, when the actuating lever 12 together with the locking bolt 13 are rotated in a direction of locking by means of a key 3, the bent end 12a of the actuating lever 12 slidable along the arcuate guide opening 11b will push the coin to the left and hence raise the bent end 25a of the detent lever 25 through intervention of the coin thereby causing the latter to be pivoted counterclockwise as viewed in FIG. 7. Since the bent end 25b of the detent lever 25 is now retreated from the circular path of stopper member 12c of the actuating lever 12, the latter i.e. the locking bolt 13 will be rotated further and easily brought into locked position. At the same time, the bent end 12a of the actuating lever 12 will come into contact with the arcuate portion 16b of the kicker lever 16 and cause the latter to be pivoted clockwise as viewed in FIG. 2. Immediately before the locking bolt 13 is swung into the locked position, the cam means 16a of the kicker lever 16 is engaged with the bent end 25a of the detent lever 25, thereby holding the latter in retreated position. At the same time, the coin is thrown into position C2 as shown in FIG. 8. In this condition, that is, in the locked condition with the key 3 retained within the lock barrel, the coin is retained in position C2 by means of the bent bottom end 36a of the second coin retainer lever 36, which bent end 36a is extended into the coin passage and adapted to come into contact with the coin at one point in the periphery thereof as shown in FIGS. 3 and 8. It is noted at this point that, as long as the key is inserted into the lock barrel and turned to locked position, the detent lever 25 is held in the position retreated from the track of the stopper member 12c of the actuating lever 12 by cooperated action of the coin retainer lever 36, the coin, and the kicker lever 16.

During the locking operation, the operating lever 31 will be pivoted counterclockwise as viewed in FIGS. 2 and 8 by means of the counter operating lug 12b of the actuating lever 12 which lug is intended for operating the counter means 33. Then, the spring 34 will be tensioned thereby causing the counter means 33 to be operated to turn a number wheel by one. On the other hand, the retainer lever 28 will be pivoted clockwise as viewed in FIG. 8 through intervention of the leaf spring 26 by the pivoted detent lever 25 and have its bent end 28a engaged with a projected end 31b of the operating lever 31 as shown in FIGS. 3 and 8.

In the locked condition, since the bent end 12a of the actuating lever 12 is disengaged from the upper end of the intermediary lever 23, the first coin retainer lever 20 will be pivoted clockwise as viewed in FIG. 8 by action of the spring 22 and come to halt when it is abutted with the guide plate 9. In this condition, an opening to the coinbox is blocked off.

When it is desired to bring the locking bolt 13 back to the unlocked position before the key 3 is removed, it is only necessary to turn the key in a reverse direction. In this case, the actuating lever 12 together with the locking bolt 13 will be brought back to the unlocked position and the kicker lever 16 will be returned merely until the bent end 16c extended into the coin passage comes to abut with the coin in the periphery thereof. In this condition, since the cam means 16a is maintained to be engaged with the bent end 25a of the detent lever 25, the latter will not be returned to normal position in which the bent end 25b stands in the track of the stopper member 12c. Accordingly, the locking bolt 13, which has been brought back to unlocked position, can be swung again into the locked position without any difficulties.

When the key 3 is removed after the locking bolt 13 is swung into locked position, the small slidable pin 4 will be retracted and the second coin retainer lever 36 will be pivoted counterclockwise as viewed in FIG. 4 about the pin 38 by action of the spring 37, thereby causing the bent end 36a to be withdrawn from the coin passage. Accordingly, the coin falls down to position C3 in FIG. 8 and is retained there by means of the first coin retainer lever 20.

When the key 3 is inserted again and turned in a direction of unlocking, the stopper member 12c of the actuating lever 12 will be separated from the bent end 25b of the detent lever 25 and the counter operating lug or bent end 12b of the actuating lever 12 will be disengaged from the operating lever 31. Then, the operating lever 31 will be returned by action of the tension spring 34 and hence the counter means 33 is restored to normal position. When the receiver pin 14 on the locking bolt 13 passes the bent portion of the spring 15, the above-mentioned operating lever will be quickly returned. At this time, the coin in position C3 will be kicked by the bent end 16c of the kicker lever 16 and dropped down into the coinbox.

Since the coin controlled lock according to this invention is constructed as described hereinabove, the locking bolt 13 can be brought into and out of locked position repeatedly as desired as long as the key is inserted, even if the lock is once locked by turning the key after depositing the coin. Therefore, even though the user has erroneously deposited into the cabinet his belongings which should not be deposited therein and locked the lock by turning the key, he can unlock the lock simply by returning the key and lock it again after he has taken out those things. This is very convenient for the user.

Furthermore, since the counter means for indicating the number of usage is actuated only by the first locking operation and will not be actuated by subsequent locking and unlocking operation prior to the removal of the key, it can indicate an accurate number of usage regardless of the repeated locking and unlocking operation as described hereinabove.

In addition, since the deposited coin is designed to be dropped into the coinbox by the unlocking operation which is carried out after the removal of the key from the locked lock, the proprietor of the cabinets can confirm that the coin has been deposited and pay back that coin to the user in case of the lock being rendered inoperable due to malfunctions.

I claim:

1. A coin controlled lock comprising a frame means defining a coin passage therein; a shaft rotatably supported by said frame means and having a lock barrel mounted thereon, a rotary locking bolt and stopper means fixedly connected to said shaft, detent means pivotally supported by said frame means and adapted to lie in the path of said stopper means to limit rotation of said locking bolt when no coin is deposited, retainer means pivotally supported by said frame means, said retainer means including a pair of spaced legs and a cam surface thereon, said cam surface being engageable with said detent means to retain said detent means in a position retracted from the path of said stopper means when a coin is deposited and said retainer means is in a pivoted position, and coin retaining means for retaining a coin in position to cause said retainer means to be maintained in said pivoted position to hold said detent means in said retracted position.

2. A coin controlled lock as defined in claim 1 including a counter means operatively associated with said coin controlled lock and including a number wheel actuated each time a coin is deposited.

3. A coin controlled lock as defined in claim 1 including a pin slidably mounted on said rotatable shaft at the innermost end thereof so as to be projected outwardly when a key is inserted and retracted when a key is removed.

4. A coin controlled lock as defined in claim 3 wherein said coin retaining means is supported for pivotal movement with respect to said frame means, and spring means normally bias-

ing said coin retaining means in one direction so as to maintain a portion thereof in engagement with said pin.

5. A coin controlled lock as defined in claim 1 wherein said coin retaining means includes a depending leg having a bent end at the tip end thereof, said bent end extending into said coin passage so as to engage a coin when a key is inserted in the lock, said bent end being retracted from said coin passage when a key is removed from the lock.

6. A coin controlled lock as defined in claim 1 wherein one 10 of said legs has a bent end adapted to engage the periphery of a coin, another of said legs having an arcuate portion, an actuating lever fixedly mounted on said shaft and including a bent end engaging said arcuate portion, said detent means including a leg having a bent end and engaging the cam means on said retainer means.

7. A coin controlled lock as defined in claim 1 wherein one 15 leg of said retainer means includes a bent end adapted to strike a coin located in the lower part of the lock into a coinbox when said retainer means is released from a detent means retaining position.

8. A coin controlled lock as defined in claim 1 wherein said 20 detent means includes a leg having a bent end extending into said coin passage which engages a coin in a first position to push said bent end upwardly, said coin retaining means including a depending leg maintained in contact with a coin in a second position so as to retain said detent means in said retracted position.

9. A coin controlled lock as defined in claim 1 wherein said 25 coin retaining means, a coin and said retainer means cooperate to continuously retain said detent means in said retracted position.

10. A coin controlled lock as defined in claim 1 including an 30 actuating lever fixedly mounted on said shaft, said actuating lever including a bent end engaging said retainer means to maintain said retainer means in a position to retain the detent means in said retracted position when the lock is in locked position.

11. A coin controlled lock as defined in claim 1 including 35 second coin retaining means for retaining a coin in a further position within the lock until the lock is unlocked by means of a key inserted in the lock.

12. A coin controlled lock as defined in claim 11 including 40 an intermediary lever, said intermediary lever including an arm, an actuating lever fixedly mounted on said shaft, said actuating lever including a bent end engageable with said arm on the intermediary lever, said intermediary lever being engageable with said further coin retaining means to retrack said further coin retaining means and release a coin into an associated coinbox.

13. A coin controlled lock as defined in claim 1 including 45 an actuating lever fixedly mounted on said shaft, said actuating lever including a bent end, said frame means including a guide plate, said guide plate having an arcuate guide opening slidably receiving the bent end of the actuating lever.

14. A coin controlled lock as defined in claim 1, including 50 a locker door a locking member moveably mounted on said door, a pivot member pivotally supported by said door and engageable with said locking bolt and said locking member so as to permit said locking bolt to lock said locking member without having a tip end of said locking bolt projecting out of the side surface of said frame means.
